MOUTH SPECULUM

Victor J. Messine, New York, N. Y., now by
judicial change of name Victor J. Terre

Application November 7, 1947, Serial No. 784,687

5 Claims. (Cl. 128—12)

1

My invention has to do with a combined mouth speculum and tongue support primarily, although not necessarily, intended for the development of facial musculature, vocal resonance, clarity of articulation, and eradication of various forms of defective speech, as lisps, stammering, stuttering, oversibilance, monotony, overinflection, nasalism, etc.

The invention is characterized by a mouth dilator operating conjunctively with a tongue support, the dilator being introduced and adjusted in the mouth of the pupil or patient to hold it wide open while the support is manipulated to force the tongue back rectilinearly in a horizontal plane.

When the jaws are fully expanded, the pupil's lips are drawn tight—with some of the upper and lower teeth showing. Then, too, the lower jaw is normally controlled by the muscles used in mastication.

By dilating the mouth and holding the tongue back in a straight horizontal line, as aforesaid, the muscles of the tongue, jaw, larynx, etc., essential to phonation, are activated, the muscles normally employed for mastication are freed, and a definite laryngeal resonance is established.

More precisely, the invention involves a mouth prop having cross openings therein, and equipped with upper and lower jaw arches by means of which the mouth may be held open; in combination with a rod which is selectively inserted transversely in any of said openings, and which has terminally swivelled thereto a novel tongue support—the outer length of the rod serving as a handle for securing the desired position of the tongue, i. e., pushed back horizontally in a straight line.

The prop and tongue support have been devised to permit their being quickly disconnected to provide for independent use when the occasion so requires.

In the drawings:

Fig. 1 is a rear elevation of the instrument.

Fig. 2 is a side elevation of the invention as applied to the mouth of a human.

Fig. 3 is a side elevation of the device, with the tongue support being shown partially in section.

Fig. 4 is a bottom plan view of the lower arch bar.

Fig. 5 is an elevation, partly in section, of a modified form of the ball and socket connection of the tongue support and handle, and

Fig. 6 is a top plan view of the upper dental arch.

Referring more particularly to the drawings, 5 55

2

designates a prop or strut in the form of a post and having at the top an upper dental arch 6, formed of rubber or similar material with a V-shaped recess 7. Below the arch, the prop is provided with a plurality of transverse, internally screw-threaded bores 8, the bottom extremity being similarly threaded and longitudinally channelled or kerfed at 9. Designed to be selectively inserted in bores 8 is a complementally threaded rod 10 carrying at its inner end a removable, vertically disposed tongue support 11, and at its outer end a knurled operating knob 12. The tongue support is constructed at its top with a converging portion 13 having a forwardly extending, relatively short lip 14, while the lower portion has a more pronounced lip 15, also deflected forwardly and formed with a medial opening 16 so as to render it bifurcated. Between the upper and lower lips, the support is flat and approximately midway at 17 is preferably enlarged at its rear to make provision for a ball and socket joint 18 with the adjacent end of rod 10. As illustrated in Fig. 5, this specific connection may be for sanitary purposes modified by enclosing the ball 18 with a detachable cap 19 to permit of ready dismantling and sterilizing of the components.

Mounted on the lower extremity of the prop is an integral transverse bar 20 having a central area 21 with a vertical opening 22 equipped with internal vertical keys 23 for engaging the channels 9, a pair of wings 24 merging laterally from the central zone 21 in opposite directions, and an offset projection 25 disposed in advance of said zone, the underside thereof carrying an insert 26 of suitable cushioning material, of V-shape in cross-section, and constituting the lower jaw arch. The upper side of each wing is concave, as at 27, to accommodate the fingers, as when it is desired to depress the bar against the lower jaw. And operating on the prop above and below the central zone, is a pair of annular nuts 28—29 which are employed to lock the bar against accidental displacement when once set in its desired position with relation to the prop.

In practice, and with particular reference to Fig. 2, the device, in its entirety, is inserted in the mouth with the operating extremity of rod 10 protruding outwardly, it being understood, of course, that initially it is determined as to which of bores 8 is best suited for positioning the rod so that the tongue support 11 will be in perfect alignment with the tongue 30. The prop is then arranged between the upper and lower jaws or teeth, that is, arch 6 with its recess 7 is caused

to engage the upper teeth 31 and insert 26 bridged over the lower teeth 32 by sliding it up or down to obtain the correct setting. With the fingers resting upon the upper concave surfaces 27 of wings 24 and forcibly depressing the bar 20, nut 28 is screwed home against the top surface of the bar, thereby firmly anchoring the device. Finally, knob 12 of rod 10 is turned appropriately so that support 11 will impinge against the tongue and constrain the latter rearwardly to the desired degree, this adjustment being expedited by virtue of the bifurcated extremity of the support which straddles the frenum under the tongue.

It will thus be seen that the instrument sustains the tongue in a rigid position and holds the mouth wide open, thereby lowering the larynx, opening the throat, and tensioning the vocal and facial musculature.

In training the tongue alone to be held up, the support and its manipulating handle can be used without the mouth prop. This is accomplished by dismantling the rod 10 with respect to the mouth prop. And whether the support is employed alone or in conjunction with the prop, it is important that the mouth be opened wide, with the tip of the tongue pointing upwards, that the bifurcated extremity of the support be placed gently over the frenum, and the tongue pressed backwards on a true horizontal line.

The tongue must not be pushed down nor up at an angle, but, forced straight into the back of the mouth, if the tongue is not supported in a straight line, the wrong muscles for proper phonation will be activated.

With the use of my device together with suitable exercises, both registers of the human voice—the lower and the falsetto—are developed. When a definite lower and falsetto register have been established, the pupil can begin to sing songs that are within the limit of one's voice with the instrument adjusted in one's mouth. As previously pointed out, the invention being centrally adjusted on the labiated opening of the mouth, holds up the tongue and maintains the jaws apart in predetermined position, thereby lowering the larynx and producing an opening in the throat.

The invention comprises a minimum number of simple components which are easily and quickly assembled or disassembled. This makes for ready sterilization, and for quantity production at a very moderate cost.

Manifestly, the service of the device may be extended to include the field of dental and surgical operations.

I claim:

1. A device of the character described, comprising in combination a mouth prop, a rod ex-

tending transversely through the prop, the rod being provided at one end with a vertically disposed tongue support and at the other end with a handle, the tongue support having outwardly divergent extremities with an intermediate flat surface, and the lower extremity being bifurcated medially.

2. A device of the character described, comprising in combination a mouth prop, a rod extending transversely through the prop, the rod being provided at one end with a vertically disposed tongue support and at the other end with a handle, the tongue support having outwardly divergent upper and lower extremities, the upper extremity being relatively short while the lower extremity is of greater length and medially bifurcated at its lower edge.

3. A device of the character described, comprising a mouth prop in the form of a single post, a tongue support carried by the prop, the upper end of the prop having a dental arch, and a transverse integral bar mounted at the lower extremity of the prop and including a central portion provided with an offset extension and a pair of longitudinally aligned wings projecting oppositely therefrom, the extension carrying a dental arch.

4. A device of the character described, comprising in combination a mouth prop, a tongue support carried by the prop, the lower extremity of the prop being longitudinally slotted and externally threaded, a transverse bar keyed to the slot, the bar having a central offset extension, a cushioning insert disposed in the extension, and lock nuts mounted on opposite sides of the bar and in mesh with the threaded extremity.

5. A device of the character described, comprising in combination a mouth prop, a tongue support carried by the prop, the upper end of the prop having a dental arch, a transverse bar adjustably mounted at the lower extremity of the prop and including a central portion and oppositely disposed lateral wings, the central portion provided with an offset extension arranged at right angles to the general reach of the bar, and a dental arch in the extension.

VICTOR J. MESSINE.
